(57) **CLAIM**

The ornamental design for a display device, as shown and described.

DESCRIPTION

FIG. 1 is a front perspective view of a first embodiment of the display device shown in a first folded state;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is a front perspective view of the display device of FIG. 1, shown in a second folded state;

FIG. 9 is a front view thereof;

FIG. 10 is a rear view thereof;

FIG. 11 is a left side view thereof;

FIG. 12 is a right side view thereof;

FIG. 13 is a top view thereof; and

FIG. 14 is a bottom view thereof.

FIG. 15 is a front perspective view of the display device of FIG. 1, shown in an unfolded state;

FIG. 16 is a front view thereof;

FIG. 17 is a rear view thereof;

FIG. 18 is a left side view thereof;

FIG. 19 is a right side view thereof;

FIG. 20 is a top view thereof; and

FIG. 21 is a bottom view thereof.

FIG. 22 is a front perspective view of a second embodiment of a display device, shown in a first folded state;

FIG. 23 is a front view thereof;

FIG. 24 is a rear view thereof;

FIG. 25 is a left side view thereof;

FIG. 26 is a right side view thereof;

FIG. 27 is a top view thereof; and

FIG. 28 is a bottom view thereof.

FIG. 29 is a front perspective view of the display device of FIG. 22, shown in a second folded state;

FIG. 30 is a front view thereof;

FIG. 31 is a rear view thereof;

FIG. 32 is a left side view thereof;

FIG. 33 is a right side view thereof;

(Continued)

FIG. 34 is a top view thereof; and
FIG. 35 is a bottom view thereof.
FIG. 36 is a front perspective view of the display device of
FIG. 22, shown in an unfolded state;
FIG. 37 is a front view thereof;
FIG. 38 is a rear view thereof;
FIG. 39 is a left side view thereof;
FIG. 40 is a right side view thereof;
FIG. 41 is a top view thereof; and,
FIG. 42 is a bottom view thereof.
In the drawings, the broken lines illustrate portions of the
display device that form no part of the claimed design in the
embodiments in which they are shown.
